US00D714991S

(12) **United States Design Patent**
Norris et al.

(10) **Patent No.:** US D714,991 S
(45) **Date of Patent:** ** Oct. 7, 2014

(54) **LAMP**

- (71) Applicant: **Grote Industries, Inc.**, Madison, IN (US)
- (72) Inventors: **Brian K. Norris**, Madison, IN (US); **Jamie H. Davis**, Madison, IN (US); **Rob E. Reese**, Madison, IN (US); **Robert Fisher**, New Albany, IN (US)

- (73) Assignee: **Grote Industries, Inc.**, Madison, IN (US)

(**) Term: **14 Years**

(21) Appl. No.: **29/471,926**

(22) Filed: **Nov. 6, 2013**

(51) LOC (10) Cl. **29-99**

(52) U.S. Cl.

USPC **D26/118**

(58) **Field of Classification Search**

USPC D26/118, 119, 120, 64, 65, 72, 124, D26/125, 138, 128, 132, 84, 85, 86, 87, 69, D26/62, 1, 2, 113, 134, 135, 89, 90, 24, 145, D26/142, 74, 63, 88; 362/147, 364, 362, 362/365, 294, 249.03, 282, 275, 190, 341, 362/249.01; D13/179, 180

(57) **CLAIM**

The ornamental design for a lamp, as shown and described.

DESCRIPTION

FIG. 1 is a perspective view of a lamp showing the new design;

FIG. 2 is a front view thereof;

FIG. 3 is a left view thereof;

FIG. 4 is a right view thereof;

FIG. 5 is a top view thereof;

FIG. 6 is a bottom view thereof;

FIG. 7 is a rear view thereof;

FIG. 8 is a perspective view of a second embodiment of a lamp showing the new design; and,

FIG. 9 is a front view of a lamp, with the left, right, top, bottom and rear views identical to the views shown in FIGS. 3-7, respectively.

The broken lines shown in the drawings illustrate portions of the lamp that form no part of the claimed design.

1 Claim, 9 Drawing Sheets
